PATENTED
SEP 10 1867

Clock Face

W. H. Cotton
Berkeley Buchanan.

John H. Belling

United States Patent Office.

JOHN H. BELLAMY OF CHARLESTOWN, MASSACHUSETTS.

Design No. 2,776, dated September 10, 1867.

DESIGN FOR A CLOCK-CASE.

The Schedule referred to in these Letters Patent and making part of the same.

TO WHOM IT MAY CONCERN:

Be it known that I, JOHN H. BELLAMY, of Charlestown, in the county of Middlesex, and State of Massachusetts, have invented a new and improved Design for Clock-Front; and I hereby declare that the following is a full description thereof, reference being had to the accompanying photograph, and to the letters of reference marked thereon.

My invention consists of a design for a clock-front, composed of emblematic symbols so arranged as to form an open-work design, as follows, to wit:

A represents a circle, intended to enclose the dial of the clock. Above the circle, and resting upon it, is a square, B, with a pair of compasses, C, and the letter "G." On the right of the square are a twenty-four-inch gauge, D, and a gavel, E, and on the left a star, F. On either side of the circle A is a pillar, H, surmounted with a chapiter, I, with a globe, J. Beneath the circle A are an hour-glass, K, and wings L, and below the hour-glass is an opening, nearly circular, M, intended for showing or starting the pendulum of the clock. On the right of the hour-glass and wings is a three-round ladder, N; on the left two parallel lines, O, enclosing an open book, P, and a circle, Q; the whole substantially as shown in the accompanying photograph.

What I claim as my invention, and desire to secure by Letters Patent, is—

A design for clock-front, substantially as shown and described.

JOHN H. BELLAMY.
